UNITED STATES PATENT OFFICE.

HUGO VAN BERESTEYN, OF BRUSSELS, BELGIUM.

ROTARY MOTOR.

No. 878,100.

Specification of Letters Patent.

Patented Feb. 4, 1908.

Application filed September 13, 1906. Serial No. 334,487.

To all whom it may concern:

Be it known that I, HUGO VAN BERESTEYN, a subject of the Queen of the Netherlands, and resident of Brussels, Belgium, have invented 5 a certain new and useful Improved Rotary Motor, of which the following is a specification.

This invention relates to a rotary motor in which the wearing away of the movable parts 10 can be compensated easily and as desired, the actuating fluid being entirely prevented from leaking, and in which the admission and expansion of this fluid are controlled by the regulator, the action of which can be regulated 15 during the working.

One form of the invention is illustrated in the accompanying drawing: Figure 1 being a longitudinal vertical section along a plane passing through the main shaft; Fig. 2 a section through A—A in Fig. 1; Fig. 3 is a plan 20 of the regulator and a sectional view of the distributing and regulating cones; Fig. 4 a section of a plate acting as a slide valve for distribution of the motor fluid and reversing 25 the motor; Fig. 5 is an inverted plan thereof; Fig. 6 the distribution valve face arranged on the upper semi-cylinder of the motor; and Figs. 7 to 11 are details.

The motor comprises a casing composed of 30 two parts, a lower semi-cylinder 1 cast in one piece with a frame base 2, and an upper semi-cylinder 3, with an extension 4, in which is a recess intended to receive a plate 38 employed in the distribution of the motor fluid, and 35 the supply thereof, as will be explained farther on. These two cylinders are joined together by bolts 79 and the casing has two covers 78. In this casing two frames 6 are arranged which are cut out so as to have a 40 perfectly circular periphery, that comes against the inside of the cylinder 1—3 and an internal circular wall that is eccentric to the latter and on which the end of the vane 7 of a rotary cylinder 8 of cylindrical form, mounted 45 on the main shaft 9 slides. Each of the frames mentioned above thus forms a working chamber in which the piston 8 acts. The frames are kept in place by a wedge 10, seated between the grooves formed in the periphery 50 of the frames and a groove formed longitudinally in the inner wall of the cylinder 1—3.

The vane of each rotary piston is loosely seated in a radial groove formed in the piston and is forced towards the internal wall of the 55 cylinder 1—3 by means of a spring 66 and by the fluid under pressure coming from the

working chamber through the passage 67, arranged towards the back surface of the vane of the piston.

Between two adjacent frames and against 60 each of two extreme frames, a fixed plate 11 is arranged. Each of these plates engages in a circular groove formed in the inner wall of the cylinder or simply flush therewith. The plates and the frames are joined one with the 65 other by means of longitudinal bolts 12 running through holes drilled in those parts.

In the example illustrated, the frames and consequently the rotary pistons are six in number, the motor shown by way of example being a triple-expansion motor, on each side of the transverse plane passing through the middle of its longitudinal axis. It is evident that the number for the piston may be varied.

75 The pistons of the part of the apparatus situated to the right of the said transverse plane are mounted at a certain angle, 180° for example, from those of the part to the left of the said plane, relatively to the position of the vanes. This arrangement gets rid of the dead point which would exist if all the pistons were keyed in the same manner.

80 From each of these working chambers a passage 51 runs which serves for carrying off 85 the water of condensation.

The main shaft 9 has two fly-wheels 76. It is supported by two plumber-blocks 13, each of which is cast with one of the covers 78 of the cylinder 1—3.

90 Each block has an opening having two walls in the form of cylindrical parts (Fig. 9) one above, the other below, and two flat vertical side walls. Into this opening a socket 68 is introduced, of similar external 95 form but of a height 3 mm. less than that of the opening in the block, so as to afford that amount of vertical play to the socket in the said opening. This socket is connected with the blocks by means of bolts 80, the holes for the passage of which in the feet 81 of this socket are made oval, so as to enable the socket to slide when it ascends. In this socket the bearing 14 is loosely arranged. Rings 82 prevent any horizontal displacement of the bearings.

100 In the bottom of the plumber block a screw hole is drilled into which a bolt 15 is screwed, with a counternut and which comes against the lower part of the sliding socket 110 68. By turning this screw in either direction, the socket and consequently the main

shaft is lowered or raised, enabling the wearing away of the pistons and of the frames to be compensated.

It is obvious that, in order to enable this vertical displacement of the main shaft to be effected, the openings for the passage of this shaft in the covers and the plates separating the working chambers are made oval in the vertical direction.

10 On to the extension 4 of the semi-cylinder 3 a cover 16 is pinned, on which, likewise by means of bolts a valve casing 17 is fixed which is employed for admitting the fluid under pressure. This cover and this casing 15 are drilled with two passages 18, one for the admission of the said fluid into the working chambers situated to the right of the cylinder, and the other for the admission thereof to the two working chambers on the left.

20 In the casing 17 two truncated pieces 19 and 20 can rotate under slight friction one within the other. The former 19 of these pieces is drilled diametrically with two passages 21 and 22, arranged diametrically 25 and at right angles to one another, one of these passages being intended for the working chambers on the right and the other for those on the left. The second truncated piece 20 has two diametrical passages both 30 drilled in the same plane longitudinally to the axis of the piece, and situated during normal working opposite the passages 18 of the cock casing 17.

The piece 19, which constitutes a distributing cone is connected with the rotary shaft of the regulator, that is actuated by the main shaft, through the medium of two chain wheels 24 and 25 and a chain 26. The speed of this piece is one-half that of 40 the main shaft. Being drilled with two holes or passages at a right angle, it admits the fluid twice for each revolution. These passages are of such a diameter as to afford a degree of admission termed, full pressure 45 at the moment of starting.

The conical piece 20, that constitutes a regulating cone, is controlled by the movable sleeve 27 of the governor when the balls 77 come away from the shaft through the action 50 of the centrifugal force. For this purpose the regulating cone may be rotated by a set of levers, in such a manner that it partly or wholly opens the passages of the distributing cone, for the purpose of obtaining an admission proportional to the requirements of the motor, at any moment.

The set of levers mentioned above comprises two arms 28 (Figs. 3 and 10) each of which is hingedly connected with the movable socket or sleeve 27 of the governor and also with a bell crank lever 29 that moves around the pivot 70. This lever 29 is bent and has a slot 30. In this slot 30 one of the ends of a two armed lever 71 engages the lever being fixed by means of a square hole,

on an extension of the same form belonging to the regulating cone. The arrangement of the two arms 29 is inversely symmetrical. The effect of this is that when the movable sleeve 27 is displaced through the action of centrifugal force, one of the ends of the lever is pushed up (Fig. 10 dotted lines) while the other is drawn down, causing a rotary motion to a certain extent of the regulating cone, and a modification of the 75 quantity of steam admitted to the motor.

The extension 4 of the upper semi-cylinder of the motor is provided with slide valve face 31 shown in Fig. 6 forming the bottom of the cavity made in this extension. In this slide valve face ports for distributing the motive fluid are drilled. Two of these openings are provided for each working chamber, that is, twelve in all for the motor shown.

The openings 32 and 33 correspond to the first two working chambers, that on the left as well as that on the right, that is to say the high pressure chambers; the openings 34 and 35 to the expansion chambers, that is to say the intermediate pressure chambers; and the openings 36 and 37 to the third, that is to say to the low pressure chambers. On this slide valve face two plates 38 slide (Figs. 1, 4 and 5) which are drilled towards their inner edge and from one side to the other with a passage 39 or 40 for the admission of the fluid under pressure to the first two cylinders (high pressure cylinders.) In the lower faces of these plates channels 41 are formed (Figs. 4 and 5) arranged for conveying into the 100 intermediate pressure chambers the motive fluid that has acted in the high pressure chambers, and channels 42 for conveying to the low pressure chambers the fluid that was expanded in these intermediate pressure chambers. These plates are also drilled with holes 43, 44 which allow the motive fluid to escape from the third series of working chambers, to the open air or into a condenser, and these discharge openings may be connected 110 with a single exhaust pipe.

The plates mentioned above can slide against a partition 47 that forms part with the semi-cylinder 3. To these plates rods 45 (Fig. 2) are laterally connected which can be 115 operated by a hand lever 46. Accordingly as the plates occupy the back or the front part of the seating in which they can move, the motor rotates in the one or the other direction. In fact, if the holes 32 (Fig. 6) coincide with the holes 39 and 40 of the distributing slide valve (back position of the same) the motor goes forwards; if, on the contrary, the holes 39 and 40 are opposite the holes 33 (position of the slide valve at 125 the front) the motor moves backwards. During the passage of the vanes over the dead point that is to say from the point *x* or the point *y* (Fig. 2) the passage from one working chamber to the other of the motive 130

fluid under pressure must be interrupted, in order that this fluid may not pass over the front face of the vane instead of expanding over the back or working surface. This obstruction is effected by means of four cones 48 (Figs. 1, 7 and 11) fixed in pairs on two shafts 49, 50. These cones are arranged on the openings corresponding to 34, 35.

The closing arrangement is so contrived that the passages are closed during the time necessary for the passing of the vanes over the dead point. For this purpose these cones are cut in the form of suitable sectors, as shown in Fig. 11. The rotary motion is imparted to these cones by the chain 26, which transmits the motion of the main shaft to the shaft of the regulator. For this purpose the shaft 49 carries a chain wheel 52 which engages with this chain. The motion is transmitted from the shaft 49 to the shaft 50 by means of two sprocket wheels 53 and 54, and a small chain 55. The motor also comprises a device by means of which the action of the regulator can be regulated as desired while the motor is working. This device is constituted as follows: The tightening ring of the regulator (Fig. 1) is furnished with two rods 57 which are in contact with a collar 69 and slide in openings formed in the fixed socket 58. This collar 69 rests against a small cylinder 59 that slides on the shaft of the regulator. This small cylinder has an external screw-thread and receives a screw sleeve 60 furnished with a milled wheel 61. This screw sleeve rests against the bracket support 62 for the regulator shaft.

If the milled wheel be turned in either direction the small cylinder 59 is moved in such a manner that the spring 63 of the regulator is compressed or extended according to circumstances and requirements.

The two holes 18 in the cover 16 can be opened or closed as desired, by slides 64 (see Figs. 1 and 2) which are operated by means of handles 65. This arrangement enables the admission of the motive fluid to one of the two series, right or left of the working chambers, or to both series at once to be suppressed.

Near each corner of the passages 18 a channel 75 is formed in the side of each frame (see Fig. 2) that serves for releasing the fluid. These passages are intended for carrying off the fluid that remains between the frames and the vanes when these have gone past the discharge passages and which, but for these passages, would compress the steam or the air.

Having now particularly described my said invention, what I claim and desire to secure by Letters Patent is:

1. In a rotary motor the combination with a suitable cylinder having an upper extension and divided into a plurality of work-

ing chambers, of a plurality of rotary vane pistons working one in each of the said chambers adapted to operate under different working pressures and keyed on a common working shaft, and means for operatively admitting working fluid to the said working chambers comprising two plates adapted to slide within a chamber in the extension of the cylinder over distributing ports formed in the said extension, there being a plurality of ports for each piston chamber and which ports are adapted to distribute working fluid to the different piston chambers, each of said plates having a passage adapted to register in different positions with the distributing ports leading to one of the high pressure chambers and said plates having channels in their lower faces adapted to register with others of the said distributing ports to convey the motive fluid that has acted in the high pressure chambers into the intermediate pressure chambers, and being provided with channels adapted to register with still others of the said distributing ports to convey the motive fluid that has acted in the intermediate pressure chambers into the low pressure chambers, and means for allowing the fluid to escape from the low-pressure chambers after acting therein comprising holes formed in the said slide plates and leading to the exterior.

2. In a rotary motor the combination with a suitable cylinder having an upper extension and divided into a plurality of working chambers, of a plurality of rotary vane pistons working one in each of the said chambers adapted to operate under different working pressures and keyed on a common working shaft, and means for operatively admitting working fluid to the said working chamber comprising two plates adapted to slide within a chamber in the extension of the cylinder over distributing ports formed in the said extension, there being a plurality of ports for each piston chamber and which ports are adapted to distribute working fluid to the different piston chambers, each of said plates having a passage adapted to register in different positions with the distributing ports leading to one of the high pressure chamber, and said plates having channels in their lower faces adapted to register with others of the said distributing ports to convey the motive fluid that has acted in the high pressure chambers, into the intermediate pressure chambers, and being provided with channels adapted to register with still others of the said distributing ports to convey the motive fluid that has acted in the intermediate pressure chambers into the low pressure chambers, and means for allowing the fluid to escape from the low-pressure chambers after acting therein comprising holes formed in the said slide plates and leading to the exterior, and means for closing.

communication between the working chambers when the piston vanes pass the dead point comprising rotary shafts and sector shaped cones on each of said shafts arranged to control the communication between the various pressure chambers.

3. In a rotary motor the combination of a cylinder comprising an upper and a lower half cylinder, a plurality of frames provided with an eccentric cylindrical opening, these frames being inserted into the said cylinder, means for preventing rotation of the said frames in the cylinder, a plurality of plates arranged between and at the ends of the said frames, means for holding the said plates and frames together, cylindrical pistons the number of which corresponds to that of the said frames and keyed on a common shaft between the said plates, a radially movable vane in each of the said pistons, means for pressing the wing against the inner wall of the said cylindrical opening of the said frames, means for compensating the wear and tear of the friction parts, means for operatively admitting pressure fluid to the piston wings, substantially as and for the purpose set forth.

4. In a rotary motor the combination of a cylinder comprising two half cylinders bolted together, a plurality of frames provided with registering eccentric cylindrical openings and snugly fitted into the said cylinder, keys engaging grooves provided in the said frames and corresponding grooves arranged in the said cylinders, plates arranged between and at the ends of the said frames, bolts holding the said frames and plates together, cylindrical pistons keyed on a common shaft and fitting between said plates a radially movable vane arranged in each of the said pistons a spring arranged behind each vane, a passage arranged in the piston and adapted to convey pressure fluid behind the said wing for pressing same against the inner wall of the said cylindrical opening of the said frames, cylinder heads secured to the ends of the said cylinder, bearings secured to the said cylinder heads and provided each with an opening having cylindrical top and bottom walls and flat side walls, a sleeve having approximately the same outlines and adjustably mounted into the said opening, the said sleeve having an inner cup shaped aperture adapted to receive the bushing, a stop ring adapted to prevent axial motion of the bushing, the said plates and cylinder heads being provided where the motor shaft passes with ovalized central holes adapted to allow radial adjustment of the said shaft, substantially as and for the purpose set forth.

5. In a rotary motor the combination with a cylinder, a plurality of working chambers, two groups of working vane pistons arranged in the said chambers, of a valve slide face arranged in the upper part of the cylinder,

two sets of admission and escape ports in the said slide face, two slides adapted to slide on the said face each corresponding to one of the said groups of pistons, admission ports, communication passages and exhaust ports adapted to register either with the admission or exhaust ports of the said slide face, means for actuating the said slides from the outside of the cylinder and means for admitting pressure fluid to the said admission ports and cutting off the said admission, substantially as and for the purpose set forth.

6. In a rotary motor the combination with a cylinder, a plurality of working chambers divided into two groups, a fresh pressure fluid admission passage for each of the said groups, a rotary valve having two diametrical passages arranged at 90° one to the other and adapted each to correspond with one of the said admission passages to allow the admission of pressure fluid and to cut it, means for rotating the shaft of the valve at half the speed of the motor shaft and means for varying the opening of the said passages according to the speed, substantially as and for the purpose set forth.

7. In a rotary motor the combination with a cylinder a plurality of working chambers divided into two groups, a fresh pressure fluid admission passage for each of the said groups, a rotary conical valve having two diametrical passages arranged at 90° one to the other and each adapted to correspond with one of the said admission passages, a conical sleeve surrounding the said conical rotary valve and provided with passages adapted to register with the said admission passages, a shaft for the said rotary valve, means for rotating this shaft at half the speed of the motor shaft, a centrifugal regulator on the said shaft, levers articulated to the movable sleeve of the said regulator, inversely arranged bell crank levers pivotally mounted on the casing of the said rotary valve and controlling sleeve, one end of each of these bell crank levers being articulated to each of the said levers, a square stud axially mounted on the said controlling sleeve, a balance lever arranged on this stud, pins on the ends of this lever, a slot in the free arm of each of the said bell crank levers and engaged by the said lever pins, and means for controlling the action of the regulator, substantially as and for the purpose set forth.

8. In a rotary motor the combination of a working cylinder, a rotary admission valve, a controlling sleeve adapted to modify the admission passage, a shaft for the said rotary valve, means for rotating this shaft at half the speed of the motor shaft, a centrifugal regulator mounted on the said shaft and actuating the said controlling sleeve, a tightening sleeve 57 for this regulator, an externally screw threaded sleeve 69 adapted to slide on the said shaft and abutting against

the said sleeve 37, an internally screw threaded sleeve 60 screwed on said sleeve 69 and abutting against a fixed part of the motor, and a milled flange 61 on the said sleeve 69, 5 substantially as and for the purpose set forth.

9. In a rotary motor the combination with a working cylinder, of a plurality of working chambers divided into two groups, admission 10 and exhaust passages for each of these chambers, means for admitting fresh pressure liquid into the two middle chambers, passages connecting the exhaust passages of each of these middle chambers to the admission 15 passage of the next adjacent chamber, revoluble cones mounted into the said passages and adapted to cut the said passages at suitable moments, a shaft for the said cones and

means for rotating this shaft at the same speed as the motor shaft, substantially as 20 and for the purpose set forth.

10. In a rotary motor the combination of a cylinder, of a plurality of working chambers, of a pressure fluid admission and exhaust passage arranged at a certain distance apart, 25 of grooves 75 arranged between the said admission and exhaust passages in the wall of the chamber, substantially as and for the purpose described.

In testimony whereof I have hereunto set 30 my hand in presence of two witnesses.

HUGO VAN BERESTEYN.
